UNITED STATES PATENT OFFICE

161,904

SINGLE ELECTRIC SHAVER DISPLAY CASE

Harry L. Carpenter, Kalamazoo, Mich., assignor to Lawrence A. Westerberg, Skokie, Ill.

Application March 23, 1950, Serial No. 8,724

Term of patent 3½ years

(Cl. D30—11)

To all whom it may concern:

Be it known that I, Harry L. Carpenter, a citizen of the United States, residing at Kalamazoo, State of Michigan, have invented a new, original, and ornamental Design for Single Electric Shaver Display Case, of which the following is a specification, reference being had to the accompanying drawing, forming a part hereof.

I claim:

The ornamental design for a single electric shaver display case, as shown.

HARRY L. CARPENTER.
